TORQUE WRENCH

Bosko Grabovac, Altadena, Calif. (½ Consolidated Devices, Inc., 818 E. Broadway, San Gabriel, Calif. 91776)

Filed May 22, 1969, Ser. No. 17,280

Term of patent 14 years

Int. Cl. D8—02

U.S. Cl. D8—24

FIG. 1 is an isometric view showing the top, side and rear end of a torque wrench embodying my new design;

FIG. 2 is a view of the rear end of my new design with normally visible parts forward of said rear end omitted;

FIG. 3 is a front end view of my new design;

FIG. 4 is a bottom view of my new design, a portion thereof being removed for ease of illustration.

FIG. 5 is an isometric view of my new design with a portion thereof being removed for ease of illustration and showing its rear end in an extended position.

I claim:

The ornamental design for a torque wrench, as shown and described.
